(57) **CLAIM**

The ornamental design for a discharge chute, as shown and described.

DESCRIPTION

FIG. 1 is a perspective view of a discharge chute according to the present invention.

FIG. 2 is an enlarged perspective view of the discharge chute shown in FIG. 1.

FIG. 3 is a side view of the discharge chute shown in FIG. 1.

FIG. 4 is a front view of the discharge chute shown in FIG. 1.

FIG. 5 is a rear view of the discharge chute shown in FIG. 1.

FIG. 6 is a top view of the discharge chute shown in FIG. 1; and,

FIG. 7 is a bottom view of the discharge chute shown in FIG. 1.

The broken line showing of the environment is for illustrative purposes only and forms no part of the claimed design.
